STACKING PUZZLE

William W. Knox, Concord, Ohio, assignor to
Mag-Nif, Inc., Mentor, Ohio

Filed May 13, 1971, Ser. No. 143,294

Term of patent 14 years

Int. Cl. D21—01
U.S. Cl. D34—15

FIG. 1

FIG. 2

FIG. 3

FIG. 1 is a top plan view of a stacking puzzle showing my new design;

FIG. 2 is a front elevational view thereof; and

FIG. 3 is a reduced perspective view thereof with the uppermost playing member, shown selectively pivoted away from the stack.

I claim:

The ornamental design for a stacking puzzle, as shown and described.
